INTERNAL COMBUSTION ENGINE FUEL SYSTEM

Thomas M. Ball, Detroit, Mich.

Application October 12, 1936, Serial No. 105,234

8 Claims.

(Cl. 261—1)

This invention relates to improvements in internal combustion engine fuel systems.

More particularly, the invention pertains to the provision in a fuel system of this character of means for accommodating selective employment of a governor.

One of the main objects of the invention is to provide an internal combustion engine fuel system in which a governor may be selectively employed or omitted, as desired, without requiring alteration of the carburetor and intake manifold of the system.

Another object of the invention is to provide in a fuel mixture system of this kind means for selectively connecting the carburetor directly to the intake manifold while maintaining communication between suction operative parts of the carburetor and a predetermined zone of the system, and for accommodating the insertion of a governor body between the carburetor and manifold while still maintaining communication between the suction operative parts of the carburetor and the system.

A further object of the invention is to provide improved gaskets which may be employed in end for end or side for side reversed positions to establish communication between the suction operative parts of the carburetor and the fuel mixture passage of the system at locations between the governor body and the intake manifold and the carburetor and intake manifold, respectively.

A still further object of the invention is to provide an improved gasket of this character which may be selectively used between the manifold and the governor or between the manifold and the carburetor to establish communication between the suction operative parts of the carburetor and a predetermined zone of the fuel mixture passage of the system when the governor is employed and not employed, respectively.

An additional object of the invention is to provide gaskets of this character which are adapted to be indexed by the means by which the parts of the fuel mixture system are secured together in order to assure proper connections between the suction operative parts of the carburetor and the fuel mixture passage of the system.

An illustrative embodiment of the invention is shown in the accompanying drawing, in which:

Fig. 1 is a fragmentary vertical sectional view of a portion of an internal combustion engine fuel mixture system embodying the invention.

Fig. 2 is a horizontal sectional view taken on the line 2—2 of Fig. 1.

Fig. 3 is a fragmentary elevational view, partly

in section, of a portion of an internal combustion engine fuel system including a governor body and embodying the invention.

Fig. 4 is a vertical sectional view taken on the line 4—4 of Fig. 3.

Fig. 5 is a plan view of a gasket embodying the modified form of the invention.

In the form of the invention illustrated in Figs. 1 to 4, inclusive, the improved internal combustion engine fuel mixture system comprises an intake manifold, generally designated by the numeral 10, having an inlet branch 11 provided with a radial flange 12 for receiving the lower end of the carburetor, generally designated by the numeral 13. The carburetor includes the main body portion 14 in which is mounted suction operable parts comprising a piston actuating member 15 and step-up valve mechanism 16 operable by the piston 15 and connected thereto by a plate 17. While the step-up mechanism is illustrated as the suction operated device in the drawing, it should be understood that this particular device is merely illustrative and that the invention may be used in conjunction with any other suction operable mechanism. Formed on the lower end portion of the carburetor body 14 is a radial flange 18 by which the body portion 14 is attached to a throttle body 19 which is also provided with a radial flange 20. Interposed between the radial flanges 18 and 19 of the carburetor body and throttle is a heat insulating separator 21.

Formed in the carburetor body 14, separator 21 and throttle body 19 are registering suction passage sections 22, 23 and 24, respectively, which communicate with each other when the parts of the carburetor are secured together in their proper relationship. Throughout the specification and claims the term "carburetor" is employed to designate the entire assembly of the carburetor body, separator and throttle body.

The throttle body 19 and inlet branch 20 have registering fuel mixture passage sections 25 and 26 which are held in alignment with each other when the carburetor is mounted on the inlet branch 11 as illustrated in Fig. 1. Formed at the lower end of the throttle body 19 is a radial flange 27 by which the carburetor is securable to the inlet branch 11. The throttle body 19 also includes a throttle valve 28 disposed in the fuel mixture passage section 25 thereof. The throttle valve 28 is operable by valve actuating mechanism, generally designated by the numeral 29.

Interposed between the flanges 12 and 21 of the manifold inlet branch 11 and throttle body 19 is a gasket 30 which is provided with an opening

31 that registers with the fuel mixture passage sections 26 and 25. This gasket is also provided with two pairs of diagonally opposite slots 32 which extend from the opening 31 to locations 5 which register with the lower end of the suction passage section 24 of the throttle body 19. The slots 32 provide communication between the suction passage sections which lead to the cylinder 33 in which the piston 15 is disposed and a location 10 in the fuel mixture passage of the system on the suction side of the throttle valve 28. The gasket 30 is provided with apertures 34 which register with apertures formed in the flanges 12 and 27 of the inlet branch 11 and the throttle body 19, respectively, and through which bolts 35 extend. The bolts 35 are preferably threaded in the apertures of the flange 12 so as to firmly secure the carburetor to the manifold 10.

The apertures 34 and bolts 35 serve as indexing 20 means for assuring proper positioning of the gasket 30 during assembly of the fuel mixture system. By virtue of the two pairs of diagonally opposite slots 32 it is not possible to improperly position the gasket 30 for the latter may be reversed side for side or end for end while still maintaining at least one of the slots in registration with the lower end of the suction passage 24.

When it is desired to interpose upon the flow of fuel mixture through the fuel system either a 30 fixed or variable control in addition to that provided by the throttle valve of the carburetor, a collar, hereinafter called a governor body, 36 may be inserted between the carburetor 13 and the manifold inlet branch 11. The governor body 36 comprises a tubular member having a fuel mixture passage section 37 which is registerable with the fuel mixture passage sections 25 and 26 of the carburetor and inlet branch respectively. Mounted in the passage section 37 is 40 a governor valve 38 which is operatively connected by a lever 39 and link 40 with any suitable governor valve controlling mechanism (not shown). The governor controlling mechanism may be of a manually actuatable type such as that employed to selectively set the governor valve 38 in a selected fixed position, or it may be of an automatic character adapted to vary the positions of the valve 38 in response to engine operating conditions or in response to operation of 50 apparatus driven by the engine.

Formed in the upper end of the governor and body 36 is a suction passage section 41 which is adapted to register with the suction passage section 24 of the carburetor. The suction passage section 41 has a port 42 leading therefrom which communicates with the fuel mixture passage section 37 of the governor body at a location on the suction side of the governor valve 38, thus assuring a communication of the suction 55 passage sections with a location in the fuel mixture passage at which vacuum is present even when the throttle and governor valves are substantially closed.

When the foregoing governor body 36 is employed, a gasket 43 is disposed between the lower flange 27 of the throttle body 19 and the upper end of the governor body 26, as illustrated in Fig. 3. The gasket 43 is provided with apertures 44 which register with apertures in the flange 27 70 and governor body 36 and through which bolts 45 extend, the bolts being preferably threaded in the apertures of the governor body. The gasket 43 is also provided with diagonally opposite pairs of apertures 46, at least one of which is adapted 75 to register with the suction passage sections 24

and 41 of the throttle body and governor body 19 and 36, respectively, when the gasket is reversed either end for end or side for side. The aperture 46, which is aligned with the suction passages 24 and 41, therefore provides communication between the fuel mixture passage of the system on the suction side of the governor valve 38 and the suction operative mechanism of the carburetor.

In Fig. 5 of the drawing is shown a modified 10 form of the invention which enables a single gasket to be used in a fuel mixture system either with or without the governor. The gasket 47, shown in Fig. 5, is provided with one pair of diagonally opposite slots 32' and one pair of diagonally opposite apertures 46'. Holes 44' are formed in the opposite ends of the gasket 47 for the reception of either the attachment bolts 35 or attachment bolts 45, depending upon whether the gasket is inserted between the throttle body 20 and the inlet branch of the manifold corresponding to the showing in Fig. 4 or between the governor body and the throttle body, corresponding to the showing in Fig. 3. It is obvious that by reversing the gasket 47 side for side it may be 25 used in either of the foregoing locations to accommodate employment of the governor body in fuel system or operation of the fuel system without the governor body as desired, while still assuring communication between the suction 30 operative parts of the carburetor and the suction zone of the fuel mixture passage on the suction side of either the throttle valve 28 alone or both the throttle valve 28 and governor valve 38.

By virtue of the foregoing construction the 35 main parts of the fuel mixture system may be of identical construction whether or not a governor body is employed therein and the gaskets which facilitate convenient adaptation of the fuel mixture system for alternative use of a governor are so constructed as to be impossible of assembly in an improper position. This feature of the invention greatly reduces assembly problems, particularly in high production lines of the character employed in the manufacture and assembly of motor vehicles and engines therefor.

Although but several specific embodiments of the invention are herein shown and described, various changes and details of construction and arrangement in the size, shape and arrangement 50 of parts may be made without departing from the spirit of the invention.

What I claim is:

1. In an internal combustion engine fuel system comprising a fuel mixture inlet branch, a carburetor including a throttle valve, and a governor body insertable between said carburetor and said inlet branch and including a governor valve, said carburetor and governor body having registerable fuel mixture passage sections and registerable suction passage sections for establishing communication between the fuel mixture passage of said system and suction operative parts of said carburetor, means for alternatively connecting said carburetor directly to said inlet branch and indirectly thereto through said governor body respectively comprising flanges on said inlet branch, carburetor and governor body, and a pair of gaskets, one insertable directly between said carburetor and said inlet branch having an opening 65 for connecting the fuel mixture passage sections thereof and having a slot extending from said opening and registerable with the suction passage section of said carburetor for connecting the same to the fuel mixture passage of said system at the 70

- junction of said carburetor and inlet branch, the other gasket having an opening for connecting the fuel mixture passage sections of said inlet branch and governor body when the latter is employed and having a port registerable with the suction passage sections of said governor body and carburetor for connecting the same to the fuel mixture passage of said system on the suction side of said governor valve.

2. In an internal combustion engine fuel system comprising a fuel mixture inlet branch, a carburetor including a throttle valve and a governor body insertable between said carburetor and said inlet branch and including a governor valve, said carburetor and governor body having registerable fuel mixture passage sections and registerable suction passage sections for establishing communication between the fuel mixture passage of said system and suction operative parts of said carburetor; means for alternatively connecting said carburetor directly to said inlet branch and indirectly thereto through said governor body respectively comprising flanges on said inlet branch, carburetor and governor body, a pair of gaskets, one insertable directly between said carburetor and said inlet branch having an opening for connecting the fuel mixture passage sections thereof and having a slot extending from said opening and registerable with the suction passage section of said carburetor for connecting the same to the fuel mixture passage of said system at the junction of said carburetor and inlet branch, the other gasket having an opening for connecting the fuel mixture passage sections of said inlet branch and governor body when the latter is employed and having a port registerable with the suction passage sections of said governor body and carburetor for connecting the same to the fuel mixture passage of said system on the suction side of said governor valve, and means adapted to extend through said flanges and said gaskets for securing adjacent flanges together and for indexing the connecting openings, slot and port of the gaskets with their respective corresponding passage sections.

3. An internal combustion engine fuel mixture system comprising an intake manifold having an inlet branch, a carburetor securable thereto having a fuel mixture passage and having a suction passage for establishing communication between a suction operative part of said carburetor and said fuel mixture passage, and a gasket between said inlet branch and said carburetor having an opening therethrough registering with the fuel mixture passages of said carburetor and said inlet branch and having a slot extending from said opening and registering with said suction passage for connecting the latter with said fuel mixture passage.

4. An internal combustion engine fuel mixture system comprising an intake manifold having an inlet branch, a carburetor having a throttle valve, said inlet branch and carburetor having register fuel mixture passage sections and having apertured flanges at the adjacent ends of said passage sections for securing said carburetor to said inlet branch, the body of said carburetor having a suction passage leading from the end thereof of adjacent said inlet branch, means extending through the apertures of said flanges for securing said flanges together, and a gasket between said flanges having an opening registering with said fuel mixture passage sections and having a slot extending from said opening to said suction pas-

sage for connecting the latter with said fuel mixture passage.

5. An internal combustion engine fuel mixture system comprising an intake manifold having an inlet branch, a carburetor having a throttle valve, said inlet branch and carburetor having register fuel mixture passage sections, and having apertured flanges at the adjacent ends of said passage sections for securing said carburetor to said inlet branch, the body of said carburetor having a suction passage leading from the end thereof of adjacent said inlet branch, means extending through the apertures of said flanges for securing said flanges together, and a gasket between said flanges having an opening registering with said fuel mixture passage sections and having a slot extending from said opening to said suction pas-

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

sage section of said governor body at a location on the suction side of said governor valve, and a gasket adapted to be selectively placed between said carburetor and said inlet passage when said governor body is not employed in said system or between said carburetor and said governor body when the latter is employed, said gasket having an opening registerable with the fuel mixture pas-

sage sections and having a slot leading from said opening and registerable with said suction passage sections of said carburetor when said gasket is in one position therebetween and having an opening registering with the suction passage sections of said governor body and said carburetor when said gasket is in a different position therebetween.

THOMAS M. BALL.
